US00D979923S

(12) United States Design Patent (10) Patent No.: US D979,923 S
(45) Date of Patent: * Mar. 7, 2023

(54) BOTTLE BELT

(71) Applicant: ZHEJIANG HUANNUO
INDUSTRIAL AND TRADING CO.,
LTD., Zhejiang (CN)

(72) Inventor: Wenhui Shi, Zhejiang (CN)

(73) Assignee: ZHEJIANG HUANNUO
INDUSTRIAL AND TRADING CO.,
LTD., Zhejiang (CN)

() Term: 15 Years

(21) Appl. No.: 29/765,762

(22) Filed: Jan. 11, 2021

(51) LOC (14) Cl. 03-01

(52) U.S. Cl.
